[57] **CLAIM**

The ornamental design for a quick release mechanism actuator for tools such as socket wrenches, as shown and described.

DESCRIPTION

FIG. 1 is a front elevational view of a quick release mechanism actuator for tools such as socket wrenches, showing our new design;

FIG. 2 is a rear elevational view thereof;

FIG. 3 is a left side elevational view thereof;

FIG. 4 is a right side elevational view thereof;

FIG. 5 is a bottom view thereof; and,

FIG. 6 is a top view thereof.

The broken line showing of a drive stud is for illustrative purposes only and forms no part of the claimed design.
